UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

CONNECTER FOR TWO-PART AUTOMOBILE DOORS.

Application filed December 9, 1922. Serial No. 605,968.

To all whom it may concern:

Be it known that I, MATTHEW R. HULL, a citizen of the United States, residing at Connerville, in the county of Fayette and State 5 of Indiana, have invented certain new and useful Improvements in Connecters for Two-Part Automobile Doors, of which the following is a specification.

My said invention relates to a door connector for vehicles having removable sections and is of the type shown in my application 10 No. 525,927, filed December 30, 1921. It is an object of the invention to provide adjusting means for varying the resilient action of 15 the connector on the upper door section as may be necessary to cause the upper part of the door to fit tightly in place but without excessive strain on the connector.

Referring to the accompanying drawings, 20 which are made a part hereof and on which similar reference characters indicate similar parts,

Figure 1 is an elevation of a door with my connector in place thereon, and 25 Figure 2 a side elevation of the connector partly in section.

In the drawings reference character 10 indicates the lower door section which forms part of the permanent body of the vehicle 30 and 11 the upper door section which is removable from the vehicle, such door portion forming part of the winter top for a car which is open in the summertime. The connector which is the subject of my invention 35 is adapted to be secured to the upper door section by means of a bracket 12 in which the horizontal rod-like part 13 of the connector is journaled, said connector having also a flattened upwardly extending part 14 secured to the door by a screw 15 or by a 40 loop, as in my application above referred to.

For securing the connector to the lower door section I have provided a bracket 16 fixed to said section by screws, or other 45 means, the horizontal part 13 being journaled in said bracket, and another bracket 17 also fixed to the door. At one end the rod-like part 13 of the connector is bent at right angles and screw-threaded as shown at 18 for 50 engagement in a threaded opening of an arm 19 extending downward over the bracket 17. This arm has a slot 20 through which passes a screw 21 having threaded engagement with 55 an opening in the bracket 17. A washer 22

is placed between the head of the screw and 55 the adjacent surface of the arm 19.

By reference to Figure 2 it will be seen that the arms 14 and 19 are not parallel but are inclined relatively to each other so that when the one is secured to the upper door section and the other to the lower door section 60 the arm 14 will tend to throw the upper section inward toward the body of the vehicle. In this way the upper part of the section 11 may be caused to strike against the fixed part 65 of the body before the lower section is closed thereby twisting the connector to hold the upper section tightly against the door jamb. Some doors are thicker than others and this condition has frequently made it necessary, 70 where the entire device including arms 14 and 19 and the body part were in one piece, to re-bend the rod of which they were formed in order to space the arm 19 sufficiently from the body of the rod. Thus a change in the 75 length of the section between angles 23 and 24 would serve to accommodate the door of the permanent body precisely, without rattling or admitting cold air. Such a change also serves to vary the torsion of the rod and 80 so the tightness of fit of the upper door section and, in the device here shown, may be made by merely rotating arm 19. The slot 85 20 facilitates assembling of the device in that the screw may be entered in the hole in the bracket 17 even if the bracket is a little too high or too low.

It will be evident to those skilled in the art that my device may be changed in various ways without departing from the spirit 90 of my invention and therefore I do not limit myself to what is shown in the drawing and described in the specification but only as indicated in the appended claims.

Having thus fully described my said invention, what I claim as new and desire to secure by Letters Patent, is:

1. A door connector comprising upper and lower arms for connection to relatively movable upper and lower door sections, one of 100 said arms being near the front edge of one door section and the other near the rear edge of the other door section, a resilient body portion extending approximately the width of the door connecting said arms and 105 twisted when the door is closed, and means for adjusting the distance between one arm and the body portion to vary the

twisting strain imparted to the said body portion on closing the door, substantially as set forth.

2. A door connector for vehicles comprising a pair of arms extending up and down for connection to relatively movable door sections, and a body portion under torsional strain when the door is closed, said body having a threaded end directed toward the interior of the vehicle body and one of said arms having threaded engagement with said end whereby the distance of the arm from the body may be adjustably varied, substantially as set forth.
3. In an automobile door having a permanent lower section and a removable rigid upper section, a connector having a resilient body extending adjacent to the dividing line between said sections, an arm for connection to the upper section at its rear end, an arm

for connection to the lower section at its front end, said arms being inclined laterally out of parallel relation whereby the upper door section is normally tilted inwardly, and brackets journaling the body near its ends extending oppositely from the respective adjacent arms and secured to the other door section from such arms, the arm connected to the lower door section being adjustable laterally relatively to the body of the connector to accommodate doors of varying widths, substantially as set forth.

In witness whereof, I have hereunto set my hand and seal at Connersville, Indiana, this 29 day of November, A. D. nineteen hundred and twenty-two.

MATTHEW R. HULL. [L. S.]
